DESIGN FOR PRESSURE REGULATING VALVE

Thomas W. Murphy, Bala-Cynwyd, Pa., assignor
to Monarch Manufacturing Works, Inc., Phila-
delphia, Pa., a corporation of Delaware

Application September 14, 1936, Serial No. 64,853

Term of patent 7 years

To all whom it may concern:

Be it known that I, Thomas W. Murphy, a citizen of the United States and a resident of Bala-Cynwyd, in the county of Montgomery and State of Pennsylvania, have invented a new, original, and ornamental Design for a Pressure Regulating Valve, of which the following is a specification, reference being had to the accompanying drawing, forming a part thereof.

Figure 1 is a front view of a pressure regulating valve showing my new design,

Figure 2 is a side view of the same, and

Figure 3 is a top plan view of the same.

I claim:

The ornamental design for a pressure regulating valve, as shown.

THOMAS W. MURPHY.
